A. J. GREENLY.
POWER CONTROL FOR AERONAUTICAL MACHINES AND THE LIKE.
APPLICATION FILED JULY 22, 1919.

1,339,332.

Patented May 4, 1920.

UNITED STATES PATENT OFFICE.

ARTHUR JOHN GREENLY, OF LONDON, ENGLAND.

POWER CONTROL FOR AERONAUTICAL MACHINES AND THE LIKE.

1,339,332.

Specification of Letters Patent.

Patented May 4, 1920.

Application filed July 22, 1919. Serial No. 312,533.

To all whom it may concern;

Be it known that I, ARTHUR JOHN GREENLY, a subject of the King of England, residing at London, England, have invented 5 certain new and useful Improvements in Power Controls for Aeronautical Machines and the like, of which the following is a specification.

This invention relates to power controls 10 for motor-driven machines. The invention is particularly applicable to aeronautical machines and to other machines or apparatus comprising parts, such as steering-devices and change-speed gearing, hereinafter 15 referred to as functioning members, adapted to be controlled by a lever which can be tilted about either and both of two axes at right angles to one another. For example, the vanes of aeroplanes, such as are operated 20 by the control-lever, could be controlled by a power control according to this invention, as also could the rudders of a submarine having one pair of rudders for steering horizontally and another pair for steering 25 vertically.

A primary object of this invention is to provide improved control apparatus whereby the functioning members of motor-driven machines can be operated at will either by 30 power alone, or by power used as an aid to manual operation, or solely by manual operation by moving one control-lever.

Another object is to combine with a control-lever or column which can be operated 35 manually for actuating the functioning members, a second control-lever which shall control motive power used for actuating the same functioning members.

A further object is to provide that the 40 second control-lever can move through a limited angle in all directions relatively to the control-column on which it is mounted, and thereby operate a slide-valve which is mounted on the control column and controls 45 motive power for operating the functioning members.

A still further object is to enable the angle through which the one lever can be tilted relatively to the other to be adjusted.

50 Another object is to enable the two control-levers to be locked in alinement one with the other.

A further object is to provide means to

vary the "feel" of the one lever movable on the other. 55

To these and other ends, the invention consists in the construction, arrangement and combination of parts described herein-after and pointed out in the claims.

One embodiment of the invention is illustrated by way of example in the accompanying drawings, wherein:—

Figure 1 is a vertical elevation, partly in section, showing one form of the power control according to the invention, 65

Fig. 2 is a bottom plan view of the control-lever shown in Fig. 1 after the valve-chest cover and the supply-pipe connected thereto have been removed from the bottom of the lever, 70

Fig. 3 is a horizontal section taken on the line 3—3 in Fig. 1, and

Fig. 4 is a like section taken on the line 4—4 in Fig. 1;

Fig. 5 is a diagram showing the valve-ports and fluid-operated devices connected thereto controlled by the control-lever shown in Fig. 1. 75

Like reference characters designate like parts in all the views. 80

Referring first to Figs. 1 to 4, a socket A pierced at its end and having a square base A¹ is mounted by means of two hollow trunnions B, arranged at opposite sides of the base, to rock in one vertical plane, for 85 example fore and aft, in a support C which in turn is mounted to rock by means of pivots D in a vertical plane at right-angles to the former plane. A control-column or lever E having one end secured in the socket A is 90 thus universally mounted and can be rocked in any direction. In the other end of this lever E is secured a ball F of a ball-and-socket joint, the socket G¹ of which is formed on the one end of a control-lever H. Secured in the other end of this lever H is a rod H¹, H², the part H¹ being tubular and carrying the solid part H² which terminates in a spherical portion or knob H³. The members H, H¹ and H² thus constitute a 100 double-ended control-lever fulcrumed on the ball F on the second control-lever E so that it can rock about either and both of two axes at right-angles to one another. The knob H³ is a sliding fit in the pocket J¹ formed in the slide-valve J which slides on

the lower face of the base A^1 of the socket A. The valve-chest cover K inclosing the valve J is provided with a tubular branch K^1 for the admission of a fluid under pressure, for example compressed air, and is secured on the base A^1 . Surrounding the pocket J^1 in this cover is a flanged sleeve L around which is coiled a spring L^1 for keeping the valve on its seat. Ports A^2 over 10 which the slide-valve can be moved are arranged symmetrically in the lower face of the base A^1 at opposite ends of two diameters thereof, located at right-angles to one another, each of these ports being in communication with either one of the hollow trunnions B or with one of the tubular branches M which are mounted on opposite sides of the base A in a vertical plane at right-angles to that containing the trunnions B.

As diagrammatically shown in Fig. 5, the trunnions B and the branches M are connected by way of pipes B^1 and M^1 , respectively, each to one of a pair of cylinders 25 N and O, respectively, each provided with a piston N^1 and O^1 , respectively. The two pistons N^1 are each connected by a band, rod or other member N^2 to a functioning member of the machine to be controlled, for 30 example to the steering vanes of the aeroplane, and the two pistons O^1 are likewise connected by bands, rods or other members O^2 to other functioning members of the machine to be controlled, for example to the 35 vanes for elevating and depressing the aeroplane. Each of these cylinders and its piston thus constitutes a power-driven relay device for actuating the vanes operatively connected thereto, and is itself controlled by 40 the slide-valve J which controls the supply of fluid under pressure to the ports A^2 and so to the cylinders N and O.

When it is desired to operate one or more of the vanes under control, the double-ended control-lever is tilted in the desired 45 direction, the knob H^3 at the lower end moves the slide-valve J over the port-face of the base A^1 out of its central or neutral position and thereby puts one or more of 50 the ports A^2 wholly or partially into communication with the branch pipe K^1 for supplying the fluid under pressure to the operating devices N, N^1 , and O, O^1 . In this manner the vanes of the aeroplane can be 55 controlled solely by power simply by actuating the above described double-ended control-lever.

As shown in Fig. 1 the upper end of the universally mounted column or lever E, 60 hereinafter referred to as the second control-lever, is screw-threaded externally and carries a ring P. In its lower position this ring constitutes a stop for limiting the rocking movement of the double-ended controlling 65 lever, so that the latter is tiltable through a

limited angle in relation to the second control-lever upon which it is mounted. When the ring P is screwed into its upper extreme position it locks the lever H to the column E, so that if the double-ended control-lever is now operated manually the slide-valve J does not move over the port-face of the base A^1 , but the second control-lever is rocked in the desired direction and the effort applied to it is transmitted by the 70 ring Q on the column E and the ties Q^1 attached thereto directly to the vanes of the aeroplane under control. It will therefore be seen that when the double-ended control-lever is locked to the second control-lever 75 80 the vanes will be controlled solely by manual operation by moving one composite control-lever, whereas when the ring P is in a lower position permitting limited relative movement between the lever H and the column E, the vanes under control will be operated at first by power alone and then, when the double-ended control-lever can be rocked no further without simultaneously 85 90 rocking the second control-lever, by power used as an aid to manual operation. Owing to the provision of this locking device P the power control can be rendered completely inoperative at any time if desired.

In order to vary the "feel," i. e. the resistance offered to movement of the double-ended control-lever, an adjustable yielding regulating-device shown in Figs. 1 and 4 is provided on the column E. This device comprises two pairs of hollow plungers R 95 arranged in two planes at right-angles to one another and slidably in externally and internally screw-threaded hollow screws T; each of these screws contains a spring S, so that one end of each plunger is pressed 100 against a squared portion H^4 formed on the rod H^2 . The other end of each of these plungers R has a flange R^1 which cannot 105 pass a shoulder T^1 formed in the screws T, whereby the movement of the spring-pressed 110 plungers in the direction of the rod H^2 is limited. Each screw T is screwed into the collar Q and the wall of the column E; a lock-nut T^2 secures each screw T in position. A threaded plug S^1 is screwed into 115 each hollow screw T and compresses the spring S therein, whereby the plungers R are normally pressed against one side of the square H^4 on the rod H^2 . It will thus be seen that when the double-ended control-lever is rocked in relation to the second control-lever one or more of the plungers R 120 will be moved against its spring S, and the farther the double-ended control-lever is rocked relatively to the second control-lever, the greater will be the resistance to motion offered by the springs S. Owing to the 125 plugs R^2 being screw-threaded the pressure of the springs S on the plungers R can be readily adjusted. When the double-ended 130

control-lever has been rocked relatively to the second control-lever this regulating-device tends to return the rod H^2 and the slide-valve J into their central or neutral position.

As shown in Figs. 1 and 3, in order that the rod H^1 , H^2 and the slide-valve J can be centered or set in relation to the ports A^2 , screws U constituting a setting-device are provided. Each of these screws is screwed at one end into the socket G^1 and projects through a hole F^1 in the ball E and abuts against the rod H^1 . As these screws are located in pairs in two different vertical planes at right-angles to one another, the rod H^1 , H^2 and, consequently, the slide-valve J can be adjusted into any desired position.

It will be appreciated that the double-ended control-lever provided by this invention does not involve any movements by the pilot other than those usually performed in manually controlling the vanes of an aeroplane in the ordinary manner.

It is to be understood that various modifications may be made in the above described power-control without departing from the spirit of the invention as defined in the claims. For example, the end of the double-ended control-lever usually operated by hand may be adapted to be operated by the pilot's foot.

What I claim as my invention and desire to secure by Letters Patent is:—

1. The combination, with a support, of a double-ended control-lever mounted thereon so that it can rock about either and both of two axes at right-angles to one another and adapted to be operated manually at one end, a port-face having ports located at the opposite ends of two diameters, and a slide-valve operatively connected to the other end of the control-lever and arranged to move upon the said port-face in all directions to and from a central neutral position.

2. The combination, with a control-lever arranged for connection to functioning members of a machine to be controlled, of a double-ended control-lever mounted thereon so that it can rock through a limited angle in relation thereto about either and both of two axes at right-angles to one another and adapted to be operated manually at one end, a port-face having ports located at the opposite ends of two diameters, and a slide-valve operatively connected to the other end of the double-ended control-lever and arranged to move upon the said port-face in all directions to and from a central neutral position.

3. The combination, with a support, of a double-ended control-lever mounted thereon so that it can rock about either and both of two axes at right-angles to one another and adapted to be operated manually at one end, a port-face having ports located at the opposite

ends of two diameters, a slide-valve operatively connected to the other end of the control-lever and arranged to move upon the said port-face in all directions to and from a central neutral position, and adjustable yielding means interposed between the control lever and its support.

4. The combination, with a universally-mounted control-column arranged for connection to the functioning members of a machine to be controlled, of a double-ended control-lever mounted thereon so that it can rock about either and both of two axes at right-angles to one another and adapted to be operated manually at one end, a port-face having ports located at the opposite ends of two diameters, a slide-valve operatively connected to the other end of the control lever and arranged to move upon the said port-face in all directions to and from a central neutral position, and adjustable yielding means interposed between the control-lever and the said control-column.

5. The combination, with a control-column arranged for connection to functioning members of a machine to be controlled, of a double-ended control-lever which comprises a tubular portion universally mounted on the control-column to rock through a limited angle in relation thereto and a central tube that is located co-axially with said tubular portion and has one end attached thereto, a port-face having ports located at the opposite ends of two diameters, and a slide-valve operatively connected to the other end of the control-lever and arranged to move upon the said port-face in all directions to and from a central neutral position.

6. The combination, with a support, of a double-ended control-lever mounted thereon so that it can rock about either and both of two axes at right-angles to one another and adapted to be operated manually at one end, a port-face having ports located at the opposite ends of two diameters, a slide-valve operatively connected to the other end of the control-lever and arranged to move upon the said port-face in all directions to and from a central-neutral position, and setting means arranged to act laterally on the said control-lever for adjusting it relatively to its support.

7. The combination, with a control-column arranged for connection to functioning members of a machine to be controlled, of a double-ended control-lever which comprises a tubular portion universally mounted on the control-column to rock through a limited angle in relation thereto and a central tube that is situated co-axially with the said tubular portion and has one end attached thereto, a port-face having ports located at the opposite ends of two diameters, a slide-valve operatively connected to the other end of the control-lever and ar-

ranged to move upon the said port-face in all directions to and from a central neutral position, and setting means arranged to act laterally on the said central tube for adjusting it relatively to the control column.

8. The combination, with a control-column arranged for connection to functioning members of a machine to be controlled, of a double-ended control-lever socketed thereon and arranged to be operated manually at one end, locking means arranged to lock the control-lever in alinement with the control-column, a port-face having ports located at the opposite ends of two diameters, and a slide-valve operatively connected to the other end of the control-lever and arranged to move upon the said port-face in all directions to and from a central neutral position.

9. The combination, with a support, of a double-ended control-lever universally mounted thereon and adapted to be operated manually at one end, an adjusting device arranged to adjust the degree to which the control lever can be tilted in relation to its support, a port-face having ports located at the opposite ends of two diameters, and a slide-valve operatively connected to the other end of the control-lever and arranged to move upon the said port-face in all directions to and from a central neutral position.

10. The combination, with a universally mounted control-column arranged for connection to functioning members of a machine to be controlled, of a double-ended control-lever socketed thereon and arranged to be operated manually at one end, an adjusting device arranged to adjust the degree to which the double-ended control-lever is tiltable in relation to the control-column, a port-face having ports located at the opposite ends of two diameters, and a slide-valve operatively connected to the other end of the control-lever and arranged to move upon the said port-face in all directions to and from a central neutral position.

11. The combination of a control-column which has one end constituting a ball and is arranged for connection to functioning

members of a machine to be controlled, a double-ended control-lever which has a socket engaging said ball and is arranged to be manually rocked thereon by one end, a ring adjustable on the control-column for adjusting the degree to which the control-lever is tiltable in relation to the control-column and for locking the control-lever in alinement with the control-column, a port-face having ports located at the opposite ends of two diameters, and a slide-valve operatively connected to the other end of the control-lever and arranged to move upon the said port-face in all directions to and from a central neutral position.

12. In apparatus for the control of power-driven machines in which a plurality of functioning members are controlled each by a fluid-pressure operated relay, the combination, with a double-ended control-lever universally mounted on the machine and adapted to be operated manually at one end, of a port-face having ports located at the opposite end of two diameters and connected each to one of the said relays, and a slide-valve operatively connected to the other end of the control-lever and arranged to move upon the said port-face in all directions to and from a central neutral position.

13. In apparatus for the control of power-driven machines in which a plurality of functioning members are controlled each by a fluid-pressure operated relay, the combination with a universally-mounted control-column arranged for connection to the said functioning members, of a double-ended control-lever universally mounted on the said control-column and arranged to be operated manually at one end, a port-face having ports located at the opposite ends of two diameters and each connected to one of said relays, and a slide-valve operatively connected to the other end of the control-lever and arranged to move upon the said port-face in all directions to and from a central neutral position.

In testimony whereof I affix my signature.

ARTHUR JOHN GREENLY.
